(57) **CLAIM**

I claim the ornamental design for a combination straw and stirrer containing granules for producing coffee- and tea-like beverages, as shown and described.

DESCRIPTION

FIG. 1 is a perspective view of a combination straw and stirrer containing granules for producing coffee- and tea-like beverages showing my new design;

FIG. 2 is a side elevational view thereof, the elevational view of the opposing side being a mirror image thereof;

FIG. 3 is another side elevational view thereof taken perpendicularly to the view shown in FIG. 2;

FIG. 4 is a top plan view thereof;

FIG. 5 is a bottom plan view thereof; and,

FIG. 6 is a perspective view showing the combination straw and stirrer containing granules for producing coffee- and tea-like beverages in use; the broken lines depict environmental structure for illustrative purposes only and form no part of the claimed design.
